UNITED STATES PATENT OFFICE

ROBERT W. DAVIS, OF OZONE PARK, NEW YORK

VEHICLE SPRING

Application filed November 10, 1927. Serial No. 232,264.

This invention relates to springs, and particularly to springs for use on vehicles.

The invention aims in general to provide an improved spring adapted for use wherever the well-known type of leaf spring is now used.

A novel feature of the present structure resides in the fact that a cover is combined with the spring in such a way that it not only 10 protects the main spring members, but also helps to carry the load imposed on the spring.

The structure of the spring includes separate tension and compression members held a fixed distance apart throughout their 15 length, and the elastic cover performs a further useful function in preventing spreading of the main spring members.

The invention also covers an improved 20 muff for binding together the ends of the spring members and for securing the end of the spring to a shackle.

A spring constructed according to this invention will be very light and strong, and since the stresses on the load carrying members are in one direction only and the spring 25 is permanently sealed against attacking elements, the spring will have an exceedingly long useful life.

While a preferred embodiment has been 30 disclosed for purposes of illustration, it should be understood that various changes may be made in the structure and arrangement without departing from the spirit and scope of the invention as hereinafter set forth 35 and claimed.

In the drawings.

Fig. 1 is a plan view of a spring constructed according to the present invention.

Fig. 2 is an elevation, partly in section, of 40 the spring shown in Fig. 1.

Fig. 3 is a section on the line 3—3 of Fig. 2.

Referring to the drawings more particularly, the spring structure comprises an upper leaf-like member 10, which in the arrangement disclosed is the tension member, and a lower leaf 11, which forms the compression member. These members are arranged with their ends in close proximity and their intermediate portions spaced a fixed distance 45 apart, and it is important that the main mem-

bers 10 and 11 be kept at fixed distances apart throughout their length while being permitted to flex. To attain this end a flexible spacing means must be interposed between the members 10 and 11, and in the embodiment shown this spacer 12 is formed of aluminum or other suitable material, and is of a shape to exactly fill the space between the main members. Slots 13 extend into the spacer from opposite sides, leaving narrow 55 flexible necks 14 along the center line of the spacer, and as a result of this construction the spacer can freely flex with the spring and acts to hold the tension and compression members 60 at fixed distances apart.

In order to protect the spring from the destructive action of moisture and other unfavorable agents, cover members 15 are placed over the spring from opposite ends. These covers are formed of any non-corrosive, elastic material capable of carrying a reasonable load, such for example as phosphor bronze. These cover members closely 70 conform to the outer shape of the spring and help to hold the main parts of the spring 75 together to form a unit.

The outer ends of the tension member 10 are bent under to form hooks 16, and the ends of the hooks 16 abut against the ends of the compression member 11, as will be clear from 80 Fig. 2. The adjacent ends of the tension and compression members must be firmly held against relative movement and must be bound in such a manner as to withstand the sheer resulting from the imposition of loads on the 85 spring. This effect can be produced by enclosing the end of the spring in a muff 17 as illustrated in the drawing.

The muff 17 is formed with a socket shaped to receive the end of the spring, and is preferably formed welded or seamless. In case the muff is made without seams its body portion 18 may be made from cylindrical stock by drilling a hole through a piece of suitable size and then taper-reaming the hole. The 90 piece is then swaged to fit over the end of the spring in the manner illustrated. The ear pieces 19 are then secured to the sides of body 18 in any suitable manner, as by welding, and form means for attaching the spring to the 100

vehicle by means of shackles. The muff is forced over the end of the spring, and pins 20 are passed through its lower side and through the end of the compression member 11, holding the muff securely in place without cutting through the tension member.

The vehicle axle 21 is secured below the intermediate part of the spring by a clamp 22, which passes over and secures the inner 10 ends of the cover members 15.

When the spring is mounted on a vehicle in the manner illustrated, the weight of the vehicle tends to press the ends of the spring downward relative to the intermediate part 15 of the spring, thereby placing the member 11 under compression and the member 10 under tension. The elasticity of the tension and compression members under the strains mentioned permits the ends of the spring to move 20 vertically with relation to the intermediate part of the spring. The amount of movement of the end of the spring under a given load depends partly on the size of the spring members and partly on the distance between 25 the members at their intermediate portions. This latter distance is shown greater in the drawings than it would normally be, the exaggeration having been made to clarify the principles of construction, but obviously 30 these mechanical details can be altered to suit any particular set of circumstances.

Since the covers 15 closely conform to the outer surfaces of the spring, they too will help to carry the load imposed on the spring, 35 the upper part of the cover being in tension and the lower part in compression.

I claim:

1. A spring comprising separate tension and compression members, and a cover 40 extending around the spring and carrying part of the load imposed on the spring.

2. A spring comprising separate tension and compression members, and a metallic cover 45 extending around the spring and carrying part of the load imposed on the spring.

3. A spring comprising a tension member and a compression member, adjacent ends of 50 the members being in proximity to each other and being held against relative movement, the members being held a fixed distance apart at another point, and a cover extending around part of the spring and carrying part of the load imposed on the spring.

4. A spring comprising a tension member 55 and a compression member, the members being in close proximity to each other at their ends, and being spaced apart at their intermediate portions, and a tapering cover member secured over each end of the spring, the 60 cover members being designed to carry part of the load imposed on the spring.

5. A spring comprising a plurality of members, the members being in close proximity 65 to each other at their ends, and being spaced apart at their intermediate portions, the ad-

jacent ends of the members being held in fixed relation, and cover members secured over each end of the spring, the cover members being designed to carry part of the load imposed on the spring.

6. A spring comprising a plurality of members, the members being in close proximity to each other at their ends, and being spaced apart at their intermediate portions, the adjacent ends of the members being held in fixed relation, spacing means for maintaining the members at proper distances apart throughout their entire length, and cover members secured over each end of the spring, the cover members being designed to carry part of the load imposed on the spring. 70

7. A spring comprising two load-carrying members, the members being in close proximity to each other at their ends and being spaced apart at their intermediate portions, clamping means for holding the adjacent ends of the members against relative movement, spacing means for maintaining the members at proper distances apart throughout their entire length, and cover members 85 secured over each end of the spring, the cover members being designed to carry part of the load imposed on the spring. 90

8. A spring comprising two load-carrying members, the members being in close proximity to each other at their ends and being spaced apart at their intermediate portions, and cover members secured over each end of the spring, the cover members being designed to carry part of the load imposed on the spring and being secured against movement outward toward the ends of the spring. 95

9. A spring comprising two load-carrying members, the members being in close proximity to each other at their ends and being spaced apart at their intermediate portions, clamping means for holding the adjacent ends of the members against relative movement, spacing means for maintaining the members at proper distances apart throughout their entire length, and cover members secured over each end of the spring, the cover members being designed to carry part of the load imposed on the spring and being secured against movement outward toward the ends of the spring. 100

10. A spring comprising a tension member and a compression member, the members being in close proximity at their ends and being spaced apart at their intermediate portions, and a tapering cover secured over each end of the spring, the cover members being secured against movement outward toward the ends of the spring. 110

11. A spring comprising a tension member and a compression member, the members being in close proximity at their ends and being spaced apart at their intermediate portions, and a tapering metallic cover secured over 115
